UNITED STATES PATENT OFFICE

2,480,747

TRIMMING MACHINE

Valentin M. Leng, Berkeley, Calif.

Application July 6, 1946, Serial No. 681,748.

7 Claims. (Cl. 125—3)

1

This invention relates to a machine for trimming or edging the ends and side edges of rectangular shaped panels made from wood shavings, excelsior or a like material which is compressed and bonded with hydraulic cement.

The panels above referred to are fully disclosed in my co-pending application entitled "Fiberboard panel and method of making same," filed August 13, 1945, Serial Number 610,677, which has been abandoned. Briefly stated, the panels disclosed in the above application are made from excelsior coated with Portland or hydraulic cement. The coated excelsior is placed in a mold and compressed, and remains under compression until the cement has taken an initial set. The compressed material in panel form is then removed and submitted to a curing action until the cement is completely set.

In actual practice the molds employed are made of wood, and as they are subjected to heavy pressure and rough handling, the panels, when removed from molds, are not always exactly square and the edges are often rough, and besides that an upward projecting fin is formed on the upper surface of the panel during the molding operation. This fin is formed at the side and end edges of the panel and completely surrounds the same. The panels thus require both trimming to square them and removal of the fin before they are ready for the market.

The object of the present invention is generally to provide a machine which will remove the upwardly projecting fin and at the same time square and cut or trim the side and end edges of the panels.

The machine is shown by way of illustration in the accompanying drawings in which:

Fig. 1 is a perspective view of the machine;

Fig. 2 is an enlarged cross-section taken on line II—II of Fig. 1;

Fig. 3 is an enlarged side elevation of the safety lever;

Fig. 4 is an end view of the same;

Fig. 5 is an enlarged side elevation of the sprocket gear and chain mechanism whereby power is transmitted to the feed rollers;

Fig. 6 is an end view partially in section of Fig. 5;

Fig. 7 is an enlarged view in section showing the cutter head spindle drive;

Fig. 8 is an enlarged view of one of the cutter heads;

Fig. 9 is an enlarged cross-section taken on line IX—IX of Fig. 8; and

Fig. 10 is a section of one end of a panel.

2

Referring to the drawings in detail, and particularly Fig. 1, A indicates an elongated main frame having a pair of lateral extending side frames such as indicated at B and C. Suitably secured to the upper surface of each side frame is an angle iron guide rail 4 and secured to the inner face of each side frame is a rack bar 5. Supported and slidably mounted between the guide rails 4—4 is a pusher head 6, and journaled at each end of the pusher head is a gear 7 (see Figs. 1, 3 and 4). This gear intermeshes with the rack bars 5—5 and thereby maintains the pusher head in a position at right angles to the guide rails while being advanced or retracted as will hereinafter be described.

The panels to be squared and trimmed are usually longer than their width. That is, they are rectangular in shape for instance four feet wide and eight feet long. These panels are placed one at a time with one side edge engaging the front edge 6a of the pusher head, and when so placed are supported by a pair of arms 6b—6b forming a part of the pusher head. The opposite ends of the panel engage the guide rails 4—4 and as such the panel is fully supported and guided during the first trimming operation, hereinafter to be described.

Supported in the main frame A are three cutter heads generally indicated at 1, 2 and 3. These cutter heads will hereinafter be referred to as the first, second and third named cutter heads. The cutter heads are identical in construction, hence the description of one will suffice.

A cutter head (see Figs. 7 and 8) consists of a vertically disposed spindle 8 supported in a bearing 9 and driven from an electric motor 10. Suitably secured on the upper end of the spindle is a head member 11 which carries a plurality of radially extending cutter blades 12. The outer ends of the blades terminate in cutting edges which are vertically disposed with relation to the vertical edge 13 of a panel such as indicated at D, and as the head carrying the cutter blades rotates at high speed, when cutting, it is obvious that the edge of a panel will be cut as indicated at 13a (see Fig. 8) when the panel is fed through the cutters in the direction of the arrow.

It was previously stated that a fin 14 was developed or formed on the upper surface edges of a panel during the molding operation (see Fig. 10) and that it is essential that this fin be removed in order to provide a finished panel. To accomplish this a second head member 15 is secured on the spindle above the head 11. This second head is provided with two radially dis-

posed cutter arms 16 (see Figs. 7, 8 and 9). The cutter arms present a flat bottom surface 17 which is disposed parallel to the upper or fin side surface of the panel to be cut and trimmed. Each cutter arm presents a wedge-shaped cutting edge 18 and this edge is curved as shown at 19 in Fig. 8 through the length of the cutter, hence as each blade sweeps across the upper surface of a panel, a draw or slicing cut is produced and the fin 14 is readily removed. This is done at the same time that the cutters 12 cut or trim the vertical edge 13 as both sets of cutter blades are mounted on the same spindle.

It was previously stated that the panel was composed of excelsior bonded with Portland or like cement. Cement is an abrasive material, hence as the flat bottom surface 17 of each cutter arm 16 sweeps across the surface edge of a panel, these lower flat surfaces are subjected to the abrasive action of the cement thereby gradually but slowly subjecting these surfaces to a grinding action which is depended upon to automatically maintain the cutting edges 18 in a sharpened condition. That is, as the surface 17 (see Fig. 9) is ground away by the abrasive, it continuously sharpens the edges 18.

In actual practice a panel to be trimmed is placed on the arm 6b (see Fig. 1) with one side edge of the panel in engagement with the front edge 6a of the pusher head 6. When so positioned, the ends of the panel will be disposed between the guide rails 4 and will be guided thereby. An operator standing between the side frames B and C will, after the panel has been positioned, release a lever 20 (see Figs. 3 and 4) and then grasp one or another of the handles indicated at 21 and push the pusher head and panel in a direction toward the elongated main frame A. In doing so the end edges of the panel will pass between the cutter heads 1 and 2. The blades 12 on the lower cutter heads will thus cut and trim the end edges of the panel while the upper cutter blades 16 will trim, cut and remove the fins 14. One or more pressure-applying rollers such as shown at 22 (see Figs. 1 and 2) may be positioned just ahead of the cutter heads 1 and 2 so as to hold the panel down in proper position while it is passing between the cutter heads. After the end edges have been cut and trimmed off, one end of the panel will align with a second pusher head indicated at 25. This is actuated by a foot treadle indicated at 26, said foot treadle being connected to the pusher 25 by a cable 27 passing over guide pulleys 28. When the foot treadle is depressed, the panel will immediately start to move in the direction of arrow b, that is on a line along the longitudinal axis of the main frame A and as such enters between the cutter heads 2 and 3, and just as the cutting operation starts, the front end of the panel enters between two power driven feed rollers indicated at 30 and 31 which are driven from an electric motor 32 through the chain and sprocket drive generally shown in Fig. 5, and once the power driven feed rollers engage the panel, the operator can release the foot treadle and return the pusher head 6 to normal position where the next panel may be placed in position. The power driven rollers 30 and 31 are continuously driven and while the panel passes between the cutter heads 2 and 3, known as the second and third named cutter heads, the side edges of the panel will be cut and trimmed and the fins removed, the finished panel finally discharging at the point indicated at 40 from where they may be removed one by one in

any suitable manner. In actual operation the panels actually made are usually four feet wide and eight feet long, and are usually either one or two inches in thickness. It is for this reason that the upper power driven feed roller 30 is provided with a screw actuated adjusting head 45 so that the spacing between it and the lower power driven roller 41 may be adjusted either to a one or two inch panel. The cutter head 11 is similarly divided into two sections as shown by the line 11a which passes through the cutter head in Fig. 7. Each head 11 is one inch in thickness, thus where two of them are placed, one on top of the other as shown in Fig. 7, a two inch thick panel is taken care of, while if one inch panels are to be handled, one head will be removed but the upper head will, of course, always be used whether two or one inch panels are being handled. The handles indicated at 21 are nothing more or less than a shaft which supports a plurality of rollers 21a. The spaces between the rollers thus function as handles. The rollers serve the function of supporting the panel to be trimmed while it is being shoved across the head to be placed in position and thereby reduce the work or labor on the part of the operator. The lever 20 is pivoted on the shaft 21. It rides back and forth on the frame with the pusher head as this is advanced or retracted by the operator but when the pusher head is fully retracted to receive a new panel, the hook-shaped end 20a of the lever drops down over the end of the frame, and as such secures the pusher head against being accidentally advanced while the panel is resting on the rollers and while it is being positioned. After the panel has been positioned in front of the pusher head, the operator merely lifts the hook-shaped end of the lever clear of the frame and at the same time pushes on the pusher head. The moment the pusher head is advanced an inch or two, the lever may be dropped and both hands of the operator are then free to operate the pusher head, and while this and other features of the invention have been more or less specifically described and illustrated it should be understood that changes may be resorted to within the scope of the appended claims and that the materials and finish of the several parts employed may be such as the experience or judgment of the manufacturer may dictate or varying conditions or uses may demand.

Having thus described my invention, what I claim and desire to secure by Letters Patent is:

1. In a machine of the character described, a frame adapted to receive and support a rectangular shaped panel, a power driven rotary cutter on the frame for cutting and trimming one end edge of the panel, a second power driven rotary cutter on the frame for cutting and trimming the other end and one side edge of the panel, a third power driven rotary cutter on the frame for cutting and trimming the other side edge of the panel, means for moving the panel in one direction between the first and second named cutters to cut and trim both ends of the panel simultaneously, and means for moving the panel after passage between said cutters towards and between the second and third named cutters to simultaneously cut and trim both side edges of the panel.

2. In a machine of the character described, a main elongated frame, a side frame extending laterally from said main frame, a first and a second power driven rotary cutter on the main frame, means on the side frame for receiving and

supporting a four-sided panel, means on said side frame for moving the panel between the rotary cutters to trim a pair of opposed side edges of the panel and onto said main frame, a third rotary cutter on the main frame, and means on said main frame for moving the panel longitudinally of the main frame and between the second and third named rotary cutters to trim the other pair of opposed side edges of the panel.

3. In a machine of the character described, a main elongated frame, a side frame extending laterally from said main frame, a first and a second power driven rotary cutter on the main frame, means on the side frame for receiving and supporting a four-sided panel, means on said side frame for moving the panel between the rotary cutters to trim a pair of opposed side edges of the panel and onto said main frame, a third rotary cutter on the main frame, means for moving the panel longitudinally of the main frame and between the second and third named rotary cutters to trim the other pair of opposed side edges of the panel, a first and a second rotary surface cutter cooperating with the first and second named rotary cutters to trim the surface edges of the panel while the first pair of side edges are being trimmed, and a third rotary surface cutter cooperating with the third named rotary cutter and with the second named surface cutter to trim the other surface edges of the panel while the second pair of side edges are being trimmed.

4. In a machine of the character described, a main elongated frame, a side frame extending laterally from said main frame, a first and a second power driven spindle journaled in the main frame, an edging cutter and a surface edge cutter secured on each spindle, means on the side frame for receiving and supporting a four-sided panel, means for moving the panel between the cutters to trim two side and surface edges of the panel and onto the main frame, a third spindle journaled on the main frame, an edging cutter and a surface cutter secured on said spindle, and means for moving the panel longitudinally of the main frame and between the second and third named spindles to trim the other two side and surface edges of the panel.

5. In a machine of the character described, a frame adapted to receive and support a four-sided panel, a power driven rotary spindle journaled on the frame, an edging and a surface edge cutter secured on said spindle, a second power driven spindle mounted on the frame, an edging cutter and a surface edge cutter secured on said spindle, a third power driven rotary spindle on the frame, an edging cutter and a surface edge cutter secured on said spindle, means for moving the panel in one direction between the first

5 and second named cutters to cut and trim two side and surface edges of the panel simultaneously, and means for moving the panel after passage between said cutters towards and between the second and third cutters to simultaneously cut and trim the other two side and surface edges of the panel.

10 6. In a machine of the character described, a compound cutter for cutting one vertical edge and the adjacent surface edge of a panel, said cutter comprising a power driven spindle, a head member secured thereon, a plurality of radially disposed cutter blades secured in said head and extending outwardly therefrom, the outer ends of said blades presenting vertical cutting edges to cut and trim the vertical side and end edges of the panel, a second head member secured on the spindle on top of the first named head, a plurality of radially extending cutter blades on said second-named head, said blades presenting lower flat surfaces engageable with the surface edges of the panel and disposed parallel to the surface of the panel, and a wedge-shaped cutting edge on each blade to cut and trim the surface edges 25 of the panel.

15 7. In a machine of the character described, a compound cutter for cutting one vertical edge and the adjacent surface edge of a panel, said cutter comprising a power driven spindle, a head member secured thereon, a plurality of radially disposed cutter blades secured in said head and extending outwardly therefrom, the outer ends of said blades presenting vertical cutting edges to 20 cut and trim the vertical side and end edges of the panel, a second head member secured on the spindle on top of the first named head, a plurality of radially extending cutter blades on said second-named head, said blades presenting lower flat surfaces engageable with the surface edges 25 of the panel and disposed parallel to the surface of the panel, a wedge-shaped cutting edge on each blade to cut and trim the surface edges 30 of the panel, and said wedge-shaped edges being disposed on a curve to produce a slicing cut.
